RETURN IDLER FOR CORD CONVEYER BELTS

William F. Bankauf, East Paterson, N. J., assignor to Hewitt-Robins Incorporated, Buffalo, N. Y., a corporation of New York

Application June 27, 1950, Serial No. 170,579

5 Claims. (Cl. 198—184)

1

In the operation of conveyor belts of which the upper or load carrying run is supported by troughing idlers, it is found that the trough shape thereby imparted to the belt tends to persist and to be retained to some extent in the lower or return run of the belt. This is particularly true of so-called cord belts. The result of this residual troughing, as it is termed herein, is that the usual cylindrical idlers which support the return run of the belt are apt to be engaged solely by the edges or marginal portions of the belt and, in course of time, considerable wear ensues. Furthermore, the degree of residual troughing or bowing persisting in the return run of various belts or under different conditions is not constant.

The object of the present invention is to provide a return idler organization which is adapted to alleviate the foregoing difficulty and which, in what may be a single, standard construction, is readily adjustable to provide adequate support for the return runs of belts having varying degrees of residual troughing.

The invention will be readily understood from the accompanying drawings, in which:

Fig. 1 is a front elevation of one form of construction embodying the invention, viewed lengthwise of the belt;

Fig. 2 is a side elevation viewed as on the line II—II of Fig. 1;

Fig. 3 is a side elevation of a modified form; and

Fig. 4 is a vertical section on the line IV—IV of Fig. 3.

In general, the invention contemplates the use of axially aligned, spaced idlers for engagement by the marginal portions only of a belt and, intermediate such idlers and horizontally spaced from them, idler means for engagement by the central or intervening portion of the belt. In such arrangement the edge portions of the belt are idler-supported on one idler axis and the intervening portion of the belt is idler-supported on a different idler axis; and, by adjustment of these two axes in relation to one another, the idlers and idler means are raised or lowered, respectively, and thereby accommodated to different curvatures of the belt.

In the form of the invention exemplified in Figs. 1 and 2, relatively short, coned idlers 1, 2 are carried by a shaft 3. These idlers are mounted adjacent the remote ends of the shaft and spaced to provide support for the edge portions of a belt 4. On a second shaft 5, parallel to but horizontally spaced from the shaft 3, are idler discs 6, 7, 8, 9, preferably of diameters somewhat larger than that of the coned idlers, so that

2

the coned idlers and at least some of the idler discs provide support for the belt through the width of its arched section.

It will be apparent that by adjusting the relative vertical positions of the shafts 3 and 5, areas of support afforded by the tops of the coned idlers and the idler discs can be caused to conform sufficiently closely to different degrees of curvature of the belt as to spread its weight over the different supporting components and thereby avoid the wear incident to the belt bearing at its edges only.

In this form of the invention, the idler shafts are carried by a cradle which is free to rock about a pivot axis extending between the shafts. The cradle structure, shafts and idler elements are in substantial balance with respect to the pivot axis; and the action of the belt itself, if of such curvature as to bear unduly on the coned idlers, or on the idler discs, serves to rock the cradle and raise into supporting position those idler elements with which it was making little or no contact.

As shown, the shafts 3, 5 are mounted in pairs of oppositely disposed brackets 10, 11 which depend from cradles 12 pivoted on pins 13 which are shown as supported from hanger brackets 14 secured to the usual stringers 15. A belt of greater than average curvature, tending to engage only the coned idlers, will rock the cradle about the axis of pins 13 in a direction to raise the idler discs into belt engaging position; and, conversely, a belt of less than average curvature, tending to engage only the disc idlers, will rock the cradle in the opposite direction to raise the coned idlers.

In the form of the invention shown in Figs. 3 and 4, provision is made for manually adjusting the relative positions of the idler shafts and locking them in any desired position. As in the previous form, brackets 16, 17 are provided for supporting the two shafts which carry the coned idlers and idler discs, respectively; and these brackets are similarly carried by cradles 18 mounted to rock about the axis of bolts 19 by which the cradles are supported from hanger brackets 20. The heads of bolts 21, 22 carried by the cradles 18 bear against the hanger brackets and, by adjustment of these bolts, the cradles can be rocked to raise or lower the respective idler elements to accommodate them to the curvature of the particular belt. Nuts 23, 24 may be provided for locking the bolts in any desired position of adjustment.

It will be understood that the two described embodiments of the invention are illustrative only and that the principles of the invention can be

applied in a variety of forms within the scope of the following claims.

I claim:

1. In a conveyor system including an endless belt, the improvement which comprises a pair of brackets disposed opposite to one another adjacent the lateral limits of the path of travel of the return run of the belt; axially aligned pivot supports for the brackets located below the said path of travel of the return run of the belt; a pair of parallel idler shafts also located below the said path of travel of the return run of the belt and supported by said brackets on opposite sides of the pivot axis of the brackets; spaced support idlers for the marginal portions of the under surface of the said lower run mounted adjacent the remote ends of one of the shafts; and spaced idler discs for supporting intermediate portions of the under surface of the said return run mounted on the other shaft intermediate the first-mentioned idlers.

2. In a conveyor system including an endless belt, the improvement which comprises a pair of brackets disposed opposite to one another adjacent the lateral limits of the path of travel of the return run of the belt; axially aligned pivot supports for the brackets located below the said path of travel of the return run of the belt; a pair of parallel idler shafts also located below the said path of travel of the return run of the belt and supported by said brackets on opposite sides of the pivot axis of the brackets; spaced support idlers for the marginal portions of the under surface of the said lower run mounted adjacent the remote ends of one of the shafts; and idler means for supporting the intermediate portion of the under surface of the said return run mounted on the other shaft intermediate the first-mentioned idlers; said brackets, shafts, idlers and idler means being substantially balanced with reference to the pivot axis of the brackets.

3. In a conveyor system including an endless belt, the improvement which comprises a pair of brackets disposed opposite to one another adjacent the lateral limits of the path of travel of the return run of the belt; axially aligned pivot supports for the brackets located below the said path of travel of the return run of the belt; a pair of parallel idler shafts also located below the said path of travel of the return run of the

5

belt and supported by said brackets on opposite sides of the pivot axis of the brackets; support idlers for the marginal portions of the under surface of the said lower run mounted adjacent the remote ends of one of the shafts; idler means for supporting the intermediate portion of the under surface of the said return run mounted on the other shaft intermediate the first-mentioned idlers; and adjustable means locking the brackets against rocking about their pivot axis.

10

4. In a conveyor system including an endless belt, the improvement which comprises a pair of horizontal, closely spaced parallel shafts mounted below the path of travel of the return run of the belt; return run supporting idlers adjacent the remote ends of one of the shafts; return run supporting idler means on the other shaft intermediate the idlers; and journal shaft supports relatively adjustable to maintain both the idlers and the idler means in contact with the belt under different degrees of residual troughing.

15

5. In a conveyor system including an endless belt, the improvement which comprises a pair of axially aligned spaced idlers; journal means supporting the idlers beneath and adjacent the marginal portions of the path of travel of the return run of the belt; idler means intermediate the said idlers; journal means supporting the idler means for rotation about an axis parallel to and adjacent the axis of the idlers and beneath the intermediate portion of the path of travel of the return run of the belt; and supporting means for both said journal means, said supporting means being relatively adjustable to maintain both the idlers and the idler means in contact with the belt under different degrees of residual troughing.
